UNITED STATES PATENT OFFICE.

HARRY DE WALLACE, OF SYRACUSE, NEW YORK, ASSIGNOR TO WALLACE M. WEEKS
AND JOHN A. PEASE, OF SKANEATELES, NEW YORK.

BOTTLE CLOSURE.

Application filed August 16, 1926. Serial No. 129,569.

This invention relates to improvements in bottle closures, designed particularly for sealing milk and other portable containers, and has for its object to provide a one-piece closure, comprising a central relatively thick and stiff disc-shaped portion that seats upon the bottom of the recess of the bottle mouth, for effecting the primary seal of the bottle, and an integral relatively thin annular convex apron, which overlays the top and inner face of the bottle mouth, for effectually shielding the pouring-surface of the mouth from dirt and germs, and for effecting a secondary seal adjacent the disc. A particular object is to provide a closure having the aforesaid features, that requires no assembling of the parts, either during or following the stamping and molding operations, and which may be stamped out of a continuous strip of uncalendared pulp-board, or like fibrous material, while the said strip is being fed through a stamping or molding mechanism; the said embossed portion providing a square-cut annular abutment, which enables the apron to be molded to conform to the flare of the bottle mouth, and which tends to expand and tighten the grip of the base of the apron against the wall of the recess immediately above its bottom ledge. And a further object is provided a closure combining a disc stopper, and a protecting apron of greater pliability than the relatively thick and inflexible disc, which may be so molded as to enable a large number of the closures to be stacked, or packed in close order in tubular magazines or cartons for shipment, and from which the closures may be fed directly into the capping machine without rehandling.

40 I attain these objects by the means set forth in the detailed description which follows, and as illustrated by the accompanying drawing, in which—

Figures 1 and 2 are respectively a fragmentary plan and an edge view of the blank strip, from which the closures are made. Fig. 3 is a plan view showing the circular body of the closure stamped out of the strip, its marginal portion being compressed, and its medial portion being embossed. Fig. 4 is an elevation of the same. Figs. 5 and 6 are respectively a top plan, and a central cross-section of the closure; showing the marginal portion of the body formed convex and the central portion depressed; the section being

taken on lines 6—6 of Fig. 5. Fig. 7 is a central vertical section; showing the closure applied to the mouth of a bottle. Fig. 8 is respectively a top plan, and an edge view, of a modified form of the closure; showing an integral segmental apron to protect a portion of the mouth of the bottle over which the contents may be safely poured. And Fig. 9 is a top plan view of the closure shown in Figs. 3 to 7 inclusive; showing a shallow depression in the top face of the disc surrounded by a protecting ledge, for facilitating printing a dealer's name, and the like, while the strip of material is passing through the cap molding machine, without danger of the wet ink being smeared.

In the drawing, 2 represents the neck of an ordinary milk bottle, and 3 the mouth, which is surrounded by an annular bead 3'. 4 represents the usual recess of the mouth, whose bottom comprises an annular ledge or seat 5, which supports the closure, as 6.

The closure 6, in the present case, consists primarily of a circular plane body of relatively thick compressible fiber, such for example, as pulp-board, which may be cut or stamped out of a plain continuous strip, as 6' (see Figs. 1, 2 and 3), the said body preferably being operated upon by suitable dies (not shown), for compressing the marginal portion, as 6^a, in a manner to materially reduce its thickness, and at the same time, leaving the medial portion 6^b embossed (see Figs. 3, 4, 5 and 7). The body 6 may then be passed between other dies (not shown), which mold the thin margin 6^a convex, and simultaneously depress the disc 6^b (see Figs. 5 and 6), and fold the inner margin of the convex apron 6^a against the periphery of the disc, to the end that when the closure 6 is applied to the mouth 3, the said disc may be readily and firmly seated upon the ledge 5 with its periphery in close contact with the adjacent wall of the recess (see Fig. 7). The second set of dies is preferably arranged to produce a relatively thin and flat closure (see Fig. 6) having a shallow concave margin, whereby large numbers of the closures may be stacked, or stored in close order, in cartons or magazines suitable for shipping and for facilitating positive and rapid feeding of the closures into the capping machines without rehandling.

The apron 6^a is preferably more or less pliable, even though it is compressed, as shown

in Fig. 3, and when the closure 6 is applied to the bottle mouth by the capping plunger, the latter is able to force the disc 6^b into the relatively deep recess 4 and effect a firm seating of the disc upon the ledge 5, as shown in Fig. 7. This latter operation materially deepens the concave portion 4'—6^b, and also compresses the apron 6^a tightly against the bead 3'. The diameter of the disc 6^b is preferably smaller than the bottom diameter of the recess, and when enlarged by the upward folding of the apron 6^a requires considerable force to properly seat the disc upon the ledge 5, as well as to effect the close contact of the base of the apron with the corresponding shoulder or wall 4' of the recess (see Fig. 7).

In Fig. 8 is shown a modification of the closure consisting of a plane compressible disc 7, substantially the diameter of the bottom of the recess, which is adapted to be seated on the ledge 5 of the recess, the same as the disc 6^b. The disc 7 is formed at one side with a segmental apron or flange 7', which is preferably compressed, the same as the apron 6^a, to a thinner gage than the disc 7, and the said segment is preferably curved or convexed to conform to and overlay a corresponding portion of the bead of the bottle mouth. Obviously, two equidistantly spaced integral segments may be formed at the opposite sides of the disc 7, as shown in the top view of Fig. 8. But ordinarily a single segment affords a relatively broad pouring surface and an adequate safe-guard. The object of the segment 7' is to provide a relatively broad pouring surface, that may be shielded from dirt and germs, and at the same time greatly reduce the area of the blank from which the closure is made, thereby cheapening its manufacture. The underside of the segments 7', may be treated with any suitable adhesive for effecting a tight seal between the bead and the segment, as indicated at 7^a, in Fig. 8.

In Fig. 9 the medial disc 6^b of the closure 6 is formed with a shallow recess or depression 6^c having a plane bottom 6^d, surrounded by a raised ledge or guard 6^e. Upon the surface 6^d may be imprinted the dealer's name,

and the grade or character of the contents of the container, while the strip 6' is passing through the cap-forming machine. The ledge 6^e tends to prevent parts of the machine or other objects from smearing the wet ink.

My invention is extremely simple. By constructing the entire closure from one piece of material, as herein shown and described, I am able to effect a tight seal of the bottle mouth, afford sanitary protection of the pouring surface of the mouth, and at the same time eliminate the usual separate reinforcing discs, together with the dies and mechanism required to produce and assemble the usual composite closures.

Having thus described my invention, what I claim, is—

1. A bottle closure comprising a disk having a thick stiff central portion and having a portion beyond the central portion compressed to a degree to provide a thin pliable member which is curved to engage over the bead of a bottle mouth and which is integral with the central portion, said member being bent upwardly at its inner side to abut the periphery of the thick stiff central portion so as to receive support therefrom.

2. A bottle closure comprising a disk having a thick stiff central portion and having a portion beyond the central portion compressed to a degree to provide a thin pliable member which is curved to engage over the bead of a bottle mouth and which is integral with the central portion.

3. A bottle closure comprising a disk having a thick stiff central portion and having a portion beyond the central portion compressed to a degree to provide a thin pliable member which is curved to engage over the bead of a bottle mouth and which is integral with the central portion, said central portion having its upper face depressed at points within its periphery to provide a printing-receiving part which lies below the raised marginal part of the central portion so as to cause the said raised marginal part to afford protection for the printing.

In testimony whereof I affix my signature.

HARRY DE WALLACE.
